Attorney:

UNITED STATES PATENT OFFICE.

ALFRED COBLE, JR., OF WESTERVILLE, OHIO.

RAIL-FASTENING DEVICE.

1,142,309.

Specification of Letters Patent. Patented June 8, 1915.

Application filed November 9, 1914. Serial No. 871,159.

To all whom it may concern:

Be it known that I, ALFRED COBLE, Jr., a citizen of the United States, residing at Westerville, in the county of Franklin and 5 State of Ohio, have invented certain new and useful Improvements in Rail-Fastening Devices; and I do declare the following to be a full, clear, and exact description of the invention, such as will enable others 10 skilled in the art to which it appertains to make and use the same.

My invention relates to improvements in rail fasteners and has for its object to provide extremely simple yet highly efficient 15 means for clamping the rails of a track upon the ties thereof.

In carrying out the above object, I employ certain novel features of construction and combination herein described and claimed 20 and shown in the drawings wherein:

Figure 1 is a side elevation of a tie constructed in accordance with my invention, showing a pair of rails resting thereon, in section; Fig. 2 is an end view of one of the 25 ties, and illustrating a side view of a portion of one rail; Fig. 3 is a top plan view of one of the ties and portions of a pair of rails thereon; Fig. 4 is a vertical transverse section as seen on the line 4—4 of Fig. 3; Fig. 30 5 is a detail transverse section as seen on the line 5—5 of Fig. 3; Fig. 6 is an inner end view of one of the clamping blocks; Fig. 7 is a bottom plan view thereof, Fig. 8 is a top plan view of one of the clamping blocks 35 showing a slightly different form of construction, and Fig. 9 is an end view, similar to Fig. 2, but showing the formation of the upper portion of the tie, when a set screw to be described, is forcibly tightened.

40 In the accompanying drawings, forming a part of this application, the numeral 1 designates a transverse I beam which constitutes a railway tie, 2 indicates a pair of longitudinal rails whose base flanges 3 rest 45 upon the upper flanges 4 of the I beam, and the numerals 5 and 6 designate respectively inner and outer rail clamping blocks.

The blocks 5 and 6 are each of rectangular 50 formation, as seen in the various figures of the drawings, and are provided with T slots 7 in their lower portions, the shanks of said slots opening through the bottoms of the blocks and extending transversely across the same, as shown. These slots receive the 55 upper portion or, in other words, the flanges 4 of the tie 1. In addition to the slots 7,

each of the clamping blocks is provided with a longitudinal groove 8 in its inner end, these grooves receiving the base flanges 3 of the rails. With the parts in this position, a set screw 9 is passed through the outer end portion of each of the clamping blocks and threaded into contact with the I beam or tie, the lower or inner ends of these set screws being pointed as seen at 10. These 60 points are projected into recesses in the tie, thereby preventing the clamping blocks 65 from slipping thereon.

In Fig. 9, I have shown the manner in which the upper flanges 4 of the I beam 1, 70 may be dished or grooved, by excessive tightening of the set screw 9, this operation being possible since the tightening of said screw draws the entire clamping block upwardly, thereby bending the flanges 4 upwardly beneath the rail 2. This becomes 75 extremely advantageous, since the I beams 1 may be made of hardened steel, the upper corners of said beams then constituting biting edges for preventing creeping of the 80 rails 2, when the parts stand as seen in Fig. 9. When the ties and rails are new and unworn, it is not necessary to tighten the screws 9 to the extent shown in Fig. 9, but when continual vibration has worn the rails 85 and clamps, it is highly expedient to so tighten said screws, for the purpose set forth.

Although in most cases, but one screw 9 is sufficient for each clamping block, three or 90 more set screws may be employed as seen in Fig. 8. These screws may be positioned as seen in this figure or in any other appropriate manner.

From the foregoing description, taken in 95 connection with the accompanying drawings, it will be seen that an extremely simple device has been provided for carrying out the object of the invention, yet that the efficiency of the device will not be impaired 100 by such simplicity.

It will be readily understood that the clamps 5 and 6 may be adjusted inwardly and outwardly upon the beams 1 to provide 105 tracks of either narrow or wide gage, these adjustments being also made when the upper portions of the beams 1 become worn after long use.

I claim:

The combination with an I beam whose 110 upper corners are sharpened, a rail resting on said beam, and fastening means abutting

one side of the rail, of a rectangular clamping block resting on the beam and having a transverse slot in one end receiving the base-flange on the other side of the rail, a 5 pair of L-shaped flanges depending from the two sides of the block and having their horizontal portions contacting with the under sides of the horizontal flanges at the top of the I beam, and an upright set screw threaded 10 downwardly through said block and bearing against the top of said I beam directly

above its upright web, whereby tightening of said screw may deflect said horizontal flanges upwardly to present their sharpened upper corners for contact with the rail. 15

In testimony whereof I have hereunto set my hand in presence of two subscribing witnesses.

ALFRED COBLE, JR.
